(57) **CLAIM**

The ornamental design for the cover for a remote device, as shown and described.

DESCRIPTION

FIG. 1 is a front perspective view of a cover for a remote device as claimed herein;

FIG. 2 is a front plan view of the cover for a remote device;

FIG. 3 is a back plan view of the cover for a remote device;

FIG. 4 is a bottom elevational view of the cover for a remote device;

FIG. 5 is a top elevational view of the cover for a remote device;

FIG. 6 is a right elevational view of the cover for a remote device; and,

FIG. 7 is a left elevational view of the cover for a remote device.

The broken line showing of environmental matter is for illustrative purposes only and forms no part of the claimed design.
